(57) **CLAIM**

The ornamental design for a setting and finger ring, as shown and described.

DESCRIPTION

FIG. 1 is a perspective view of a setting and finger ring showing my new design;

FIG. 2 is a front elevation view of the ring and setting of FIG. 1;

FIG. 3 is a side, elevation view of the ring and setting of FIG. 1; and,

FIG. 4 is a top, plan view of the ring and setting of FIG. 1. The broken lines are for illustrative purposes only and form no part of the claimed design.
